GLASS DOOR LOCK

Filed Aug. 16, 1944.

UNITED STATES PATENT OFFICE

2,338,851

GLASS-DOOR LOCK

Frederic K. Heyer, Stamford, Conn., assignor to
The Yale & Towne Manufacturing Company,
Stamford, Conn., a corporation of Connecticut

Application August 16, 1941, Serial No. 407,149

2 Claims. (Cl. 70—14)

This invention relates to a door lock and more particularly to a lock for doors of the type in which it is undesirable or impossible to mount a lock of conventional design.

Even more particularly, my invention relates to a lock especially adapted for use with hardened glass doors. Such hardened glass doors are incapable of being cut once they are hardened, so that the mounting of a lock on such doors, presents a considerable manufacturing problem. By using the lock of my invention, it is possible to lock such hardened glass doors without complicated and costly lock installations.

As a feature of my invention, I utilize a lock which is readily assembled and removed relatively to a floor plate over which swings the door or doors to be locked. As a further feature of my invention, my door lock is adapted to be locked in assembled relation to a floor plate through manipulation of a key operated means mounted therein, and to be secured in assembled and locked relation to the floor plate while preferably being adapted for some pivotal movement on the floor plate to adjust itself to particular closed positions of the door or doors to be locked.

As still a further feature of my invention, the floor plate is adapted for cooperation with two locks, one for each face of the door or doors to be locked, the entire assembly being adapted for use on the many varied types of installations which are possible, and which are found in existing buildings.

I have thus described my invention generally in order that the operation and construction thereof to be hereinafter presented, may be more clearly understood. Naturally, the conception on which my invention is based, may be embodied in forms other than that which I shall hereinafter show and describe, so that my patent claims should not be unduly limited in scope.

Referring now to the drawing, Fig. 1 is a front view of a pair of doors showing my lock in locking relation thereto. Fig. 2 is a perspective view of a pair of doors adapted to be locked by a pair of door locks embodying my invention. Figs. 3 and 4 are respectively sections taken along lines 3—3 and 4—4 of Fig. 1.

Referring now more particularly to the drawing and especially Fig. 1, I show there a pair of swinging glass doors 10 and 11. To the upper and lower inside corners of the doors there are secured hinge mounting plates 12 of usual construction, whereby the doors are mounted for swinging movement relatively to the door frame 13. In the actual manufacture of hardened glass doors, the hinge mounting members 12 are as-

sembled prior to the hardening of the glass doors, it being impossible to cut the glass once it is hardened without completely destroying it, all as is known to those skilled in the art.

5 It will be now appreciated that to install lock units in the doors 10 and 11, would require the addition of further structural elements, and the further cutting of the doors, all of which would have to be done prior to the hardening of the doors. Since each type of lock installation is dependent on the particular door installation, and since there are so very many types of door installations, it is readily seen that it is difficult to maintain a stock of finished doors equipped with locks to meet all possible situations. Through the utilization of my invention, it is unnecessary to mount a lock on either of the doors 10 and 11, thereby eliminating the necessity of maintaining a stock of doors equipped with locks to meet various installation requirements. I believe that this advantageous feature of my invention will now be quite clear to those skilled in the art.

Referring now more particularly to Figs. 2, 3 and 4, it will be noted, that the doors 10 and 11 swing relatively to a floor 14 and that the lower edges of the doors are in close juxtaposition to the floor surface so as to eliminate drafts. A floor or socket plate 15 is secured to the floor 14 and lies with its upper surface 17 in alignment with the surface of the floor itself. A portion of the floor or socket plate 15 extends beyond each face of the doors 10 and 11, when the doors are in their closed position illustrated best in Figs. 2, 3 and 4. Socket openings 18 are formed in the plate 15 at each side of the closed positions of the doors, each of these socket openings 18 being in alignment with an opening 19 in the floor 14.

For cooperation with each of socket openings 18, I employ the winged bolt 20 of a locking member 21. This locking member 21 preferably comprises an abutment portion 22 and a plate portion 23, with a pin tumbler cylinder 24 held fixed within the abutment portion 22. The key plug 25 of the cylinder 24 is preferably formed for rotation with the bolt 20, when the key plug is released by a key, all in a manner which will be quite apparent to those skilled in the art and which forms no part of this invention. A dust cover 26 is pinned at 27 to the cylinder lock 24 for rotation into position to cover and protect the key plug 25, all of which will be understood by those skilled in the art.

The plate portion 23 of the locking member 21 is preferably equipped with a resilient facing 28 adapted to be applied to the faces of doors 10 and 11, when the locking member 21 is in lock-

ing position as illustrated in Figs. 3 and 4. It will now be quite obvious that with the doors 10 and 11 in their position of Fig. 2, the locking member 21 may be readily assembled relatively to the socket plate 15 through the insertion of the winged bolt 20 into the socket 18 and with the plate portion 23 fitted against the faces of the doors, after which, the key plug 25 and the bolt 20 are rotated together from the position of Fig. 2 to the position of Figs. 3 and 4, or approximately 90 degrees. This positions the winged bolt 20 relatively to socket 18 so that the locking member 21 cannot be lifted upwardly out of locking position, all of which will be now quite apparent. The key plug 25, of course, locks the bolt against rotation relatively to the locking member 21. It will, moreover, be appreciated that with the door locking member or members 21 assembled relatively to the doors 10 and 11, it is possible to rotate the door locking members so that they may properly align their plate portions 23 to the faces of the doors. This movement will not disturb the locking relation between the winged bolts 20 and the sockets 18 of the floor or socket plate 15. Those skilled in the art will appreciate that it requires a rotation of 90 degrees to rotate the winged bolts out of locking position, and that such rotation may only be imparted thereto by rotation of the key plug 25 to the position of Fig. 2 from the position of Figs. 3 and 4.

Those skilled in the art will now appreciate the adaptability of my invention to various glass door installations, but, it may be well to describe its action in a typical and rather common installation, as for example, the doors of Fig. 2 which are of a type adapted for outward and inward swinging movement. There, the proprietor on leaving the store, will first lock to the floor plate 15, an inside locking member designated by reference numeral 21¹ in Fig. 2. He will then leave the store through swinging one or the other of the doors 10 and 11, while holding the locking member 21 in his hand. The doors 10 and 11 will now be allowed to close against the plate portion 23 of the locking member 21¹, or into their position of Fig. 2. The locking member 21 may then be readily applied to the floor plate 15 as was already described, leaving the pair of doors securely locked from the inside and outside as seen in Figs. 3 and 4.

Should the proprietor of the store desire to lock the doors against inward swinging while allowing the doors to swing outwardly, it is obvious he will lock the member 21¹ relatively to the floor or socket plate 15, but will not apply the locking member 21 to the floor plate. The doors 10 and 11 will now be adapted for outward swinging movement but will not be capable of swinging inwardly.

It will be further appreciated that where but one glass door is used, the socket or floor plate 15 is mounted merely under that one door, and the operation of the locking members is exactly the same as has heretofore been described except that only one door is controlled.

It is further obvious that in some installations, where economy is desired, one of the locking members, as for example the locking member 21¹ in Fig. 2 may be formed without a cylinder lock and with merely a winged bolt 20 fixed to the abutment portion 22. Then, with both doors 10 and 11 out of closed position, the lock member 21¹ may be assembled relatively to the socket opening

18 by vertical movement of the bolt 20 into the socket 18, and then by rotation of the entire locking member. In other words, the engagement to be made is in the nature of a bayonet joint.

5 Thereafter, the two doors 10 and 11 may be locked by the outside locking member 21, just as has already been shown and described. It is thought that the operation and general structure of my invention will now be clearly understood.

10 I now claim:

1. A locking means for a door wherein a locking plate is mounted in the floor beneath the door and said plate is provided with a wing bolt opening at each side of the door for receiving the 15 wing bolt of a locking member adapted to lie juxtaposed to the face of the door to prevent swinging thereof, said locking member comprising a casing portion for housing a key operated locking mechanism, a pair of oppositely extending wing portions secured to said casing portion to form an integral part thereof, a key rotated element forming part of said key operated locking mechanism and rotatable relatively to said casing portion when key operated and normally 20 locked to said casing portion for movement bodily therewith, a wing bolt rotatable with said key rotated element relatively to said casing, said wing bolt being adapted for entry into said wing bolt opening in said locking plate and for rotation thereafter relatively to said opening and said casing into locking relation to said locking plate, said wing bolt opening being so related to said wing bolt that substantial rotation may thereafter be imparted to said wing bolt and locking member as a unit by the door without bringing said wing bolt into release alignment with said wing bolt opening.

2. A locking means for a door wherein a locking plate is mounted in the floor beneath the door and said plate is provided with a wing bolt opening at each side of the door for receiving the wing bolt of a locking member adapted to lie juxtaposed to the face of the door to prevent swinging thereof, said locking member comprising a casing portion for housing a key operated locking mechanism, a pair of oppositely extending lateral wings secured to said casing portion to form an integral part thereof, a key rotated element 45 forming part of said key operated locking mechanism and rotatable relatively to said casing portion when key operated and normally locked to said casing portion for movement bodily therewith, a wing bolt rotatable with said key rotated element relatively to said casing and normally locked with said key rotated element for rotation with said casing, said wing bolt being adapted for entry into a wing bolt opening in said locking plate and for rotation thereafter with said key rotated element relatively to said locking plate and said casing into locking relation to said locking plate while said lateral wings are in alignment with the door, said wing bolt opening being so related to said wing bolt that substantial rotation may thereafter be imparted to said wing bolt and locking member as a unit without bringing said wing bolt into release alignment with said wing bolt opening, said locking member and door mutually interlocking through said laterally extending wings to prevent rotation of said wing bolt with said locking member into release alignment with said wing bolt opening.
